FIG. 10

UNITED STATES PATENT OFFICE

2,616,532

REVERSIBLE VERTICALLY SLIDING WINDOW ATTACHMENT FOR GUARD WINDOWS

Lee D. Bayley, Springfield, Ohio

Application March 10, 1949, Serial No. 80,674

13 Claims. (Cl. 189—64)

1

This invention relates to guard windows, although not necessarily so limited, and more particularly to a closure assembly for a ventilating area for the same.

In guard windows, such as psychiatric guard windows, detention windows and windows for use in prisons and the like, wherein the muntin bars or bars simulating muntin bars, are used as detention bars, certain spaces may be left vacant or unglazed for use as a ventilating area. When this is done, it may be necessary to provide a closure for the ventilating area.

An object of this invention is to provide an attachment for the guard window, such that the closure may be slid from a closed position to an open position and vice versa, furthermore, the closure may be actuated into another position where it may be easily cleaned, repaired, painted, reglazed, repainted and the like, without being detached from the guard window.

Another object of this invention is to provide a guide for use with a sliding closure for a ventilating area, wherein the guide is jointed, so that when the closure is actuated into open position one portion of the guide may be rotated so as to turn the closure inside out.

Other objects and advantages reside in the construction of parts, the combination thereof and the mode of operation, as will become more apparent from the following description.

In the drawings,

Figure 1 is an inside elevational view of a window assembly including an attachment for a closure used in closing the ventilating area.

Figure 2 is a vertical sectional view taken substantially on the line 2—2 of Figures 1 and 3.

Figure 3 is a horizontal, cross sectional view taken substantially on the line 3—3 of Figures 1 and 2.

Figure 4 is a fragmentary, cross sectional view showing the closure adjusted into open position and the guide section rotated so as to turn the closure inside out.

Figures 5 and 6 are fragmentary, detail views of an upper and lower corner of the guide structure surrounding a ventilating area of a guard window.

Figure 7 discloses a cross sectional view of a modification.

Figure 8 is an enlarged cross sectional view, taken substantially on the line 8—8 of Figure 7, with the auxiliary frame aligned with the fixed frame.

Figure 9 is a fragmentary view looking in the direction of the arrows 9—9 of Figure 8.

2

Figure 10 is an enlarged cross sectional view, taken substantially on the line 10—10 of Figure 7.

Referring to the drawings, the guard window or detention window proper includes a top frame member 10, the horizontal muntin bars 12 and the vertical muntin bars 14. These may be conventional muntin bars, T-shaped in cross section, which, in addition to functioning as muntin bars, also function as detention bars or guard bars, preventing the ingress or egress of human beings through the window. The spaces 16 in the upper half of the window, as seen in Figure 1, are glazed. The openings 18 between the guard bars in the lower half, as viewed in Figure 1, remain unglazed and may be used as a ventilating area. The window assembly described thus far may be a conventional window.

The spaces left vacant for a ventilating area may extend to the bottom of the window and may extend across the width of the window, or these spaces may constitute an area less than one-half the height of the window and an area less than the width of the window. This is a matter of choice, depending entirely upon the particular requirements. Furthermore, this area forming the ventilating area may be relocated after the window is installed, so as to better meet the requirements either due to changed conditions or due to conditions that had not been anticipated at the time the ventilating area was first located. Also, the ventilating area may be changed in size from time to time by merely providing a proper attachment for closing the ventilating area, which attachment will now be described.

This attachment includes a lower frame portion 20 that is provided with a sill member 22, having a horizontal portion 24, and a pair of downwardly projecting flanges 26 and 28 straddling the upwardly directed flange 30 of the transverse muntin bar 12 extending across the bottom of the ventilating area. The flange 26 makes a line contact with the flange, to thereby prevent water being drawn through the juncture between the sill 22 and the supporting muntin bar 12 by capillary attraction. The flange 28 is provided with a horizontal flange portion 32 seated against the face of the muntin bar 12 and providing a cavity 34 for insulating material, sealing the juncture between the sill member 22 and the muntin bar 12. The sill member 22 is provided with a flange 40 extending upwardly and a horizontal inwardly projecting flange 42. The flanges 40 and 42 provide a seat upon which

the closure rests when in closed position, as will be described more fully later.

As may best be seen by referring to Figure 3, the stationary lower frame portion 20 includes a pair of lateral channel members 50, one on either side of the ventilating area, each provided with an inwardly directed channel 52. The wall 54 of each member 50 is provided with a channel supporting a strip of weather-proofing material 56, sealing the juncture between member 50 and the adjacent vertically disposed muntin bar 14. Member 50 may also be provided with a flanged portion 58, to which a woven wire screen 60 is secured in any suitable manner. The sill 22 and members 50 are joined by a mitered joint, as best seen in Figure 6. An L-shaped bracket 57 is riveted by rivets 59 to the sill 22 and to a member 50 to provide a rigid corner. Across the top of the stationary frame portion 20 extends a bar 70, as best seen in Figures 2 and 4. This bar 70 is provided with a channel housing a strip of weather-proofing material 72, so as to seal the fourth side. Member 70 provides a support for the upper edge of the screen 60. Members 50 and the bar 70 are secured together by L brackets 61, as best seen in Figure 5. Member 70 is also used to fixedly secure the closure 20 in position by suitable means which will now be described.

A lug 74 is positioned in the corner between two intersecting muntin bars, one of which extends across the top of the ventilating area. A bolt 76 provided with a round head is positioned against member 70 and held in position by a suitable nut 78 that preferably has a round periphery and may be removed only by the use of a specially designed tool, so as to prevent the inmates from removing the fixed portion 20. The bolt 76 cooperates with the lug 74 to clamp the fixed frame portion against the muntin bars surrounding the ventilating area. The flange 26 prevents outward movement from the bottom.

The stationary frame portion 20 provides a frame for a movable closure 80, glazed by suitable window panes 82 seated in the bottom frame member 84, the top frame member 86 and the side frame members 88. The bottom frame member 84 of the movable closure is provided with an inwardly directed lip portion 90 that prevents condensation which may form on the glass or window pane 82 from running down so as to seep in between the bottom frame member 84 and the flanges 40 and 42. Angle bars 91 cooperate to form a T-shaped light weight muntin bar for the movable closure 80.

The movable closure 80 may be raised so as to open the ventilating area. In order to provide a guard for the closure 80 above the fixed frame, an auxiliary frame 92 is located above the fixed frame, which auxiliary frame will now be described.

Members 100, one forming a continuation of the side members 50 and identical in cross sectional area, extend upwardly from members 50 and are attached thereto by suitable hinges 102. A transverse angle bar 104, as best seen in Figure 2, connects the tops of members 100. Members 50 provide channels for the ventilating closure to be raised, so as to open the ventilating area. The screen 60, however, extends over the ventilating area, even though the closure 80 is raised into up position.

In order to prevent the auxiliary frame including members 100 and 104 from tipping about the hinges 102, so as to drop from the position shown

in Figure 2 to that shown in Figure 4, members 50 are secured in position by studs 106, only one of which has been shown. Each stud 106 is provided with a round head 108 that cannot conveniently be unscrewed from the tubular nut-like member 110 without the use of a special tool. Tubular nut-like member 110 is fixedly secured to a vertically disposed bar 112 located between the glazing 114 and the downwardly projecting flange of top member 10 and the upwardly projecting flange of the adjacent muntin bar 12. The bolt 106 cooperates with the tubular member 110 to removably clamp the auxiliary frame in a stationary position.

In the event it is found desirable to wash the outside of the window pane of the closure, or in the event a window pane is broken, the window pane 82 may be replaced by opening the closure 80 so as to be located between the bars 100. Then by unscrewing the stud bolts 106 from the tubular members 110, the closure 80, together with the frame members 100 and 104, which constitute the auxiliary frame, may be moved into the position shown in Figure 4. When in this position the outside of the glazing 82 may be washed, the putty 120 may be repaired or in the event of a broken window pane, it may be removed and a new window pane 82 inserted and re-putted in readiness for use. When the closure has been serviced, the auxiliary frame, including members 100 and 104, together with the closure 80, may be raised to the position shown in Figure 2, the stud bolts replaced by the use of a special tool, so as to secure the auxiliary frame in position, and the closure dropped into the full line position shown in Figure 2.

In the modification disclosed in Figures 7 to 10 inclusive, the lower frame portion 130 is substantially identical to the corresponding portion in the preferred embodiment. The auxiliary frame 132 is substantially identical to the auxiliary frame 100. The closure 134 is slidably mounted in the main frame 130 and the auxiliary frame 132.

As may best be seen by referring to Figure 8, the side frame member 136 of the movable closure 134 has attached thereto a weather stripping spring 138 that may be secured at 140 to the side frame member 136. This weather stripping spring 138 is provided with a small loop 142, positioned between the auxiliary frame 132 and a pair of ribs 144 and 146 integral with the side frame member 148 of the main frame 130. A loop 150, formed on the end opposite the loop 142, provides a bight into which the flange 152 projects. This weather stripping member is preferably made from suitable resilient material, such as brass.

A channel-shaped operator 160, pivotally mounted upon a pivot 162 extending into the main frame and supporting a spacer member 164, functions to hold the auxiliary frame in a tilted position when released and in a fixed position when locked.

A shoe 170 is pivotally mounted upon a pivot 172 fixedly mounted in the side frame of the auxiliary frame 132. This shoe 170 is mounted in the upper end of the operator 160. In order to limit the angle of inclination of the auxiliary frame 132, a stop 174 is fixedly mounted in the channel of the operator 160, so as to arrest the movement of the shoe 170. The position of this stop determines the angle of inclination of the auxiliary frame when swung into open position.

The operator 160 is also used to lock the auxiliary frame 132 against the main frame of the

window. By adjusting the auxiliary frame into dotted position, the operator 160 will then extend parallel to the sides of the fixed frame and to the side of the auxiliary frame. The operator 160 may be locked in this position by means of a cam-like latch 180 pivotally mounted upon a pivot 182. This cam-like latch 180 is mounted for limited position about the pivot 182 and may be projected out through the frame through a slot 184 into the full line position shown in Figure 8, so as to engage the side of the operator 160 to prevent this operator from rotating about the pivot 162, thereby locking the auxiliary frame into position parallel to the main frame.

Although the illustrating device discloses a closure that is raised to open the ventilating area, this closure may be lowered to open the ventilating area in the event the ventilating area is positioned above the glazed area. Furthermore, the ventilating area could be located to one side of the glazed area, in which event the auxiliary frame could be laterally disposed with respect to the fixed frame for the closure. When thus arranged, the closure could be slid sidewise to open and close the ventilating area. Also, the auxiliary frame might extend over the ventilating area and the fixed portion of the frame extend over the glazed area.

Furthermore, the closure assembly, instead of being located on the inside of the window, may be located on the outside of the window. Especially is this desirable when the closure is opened and closed by remote control mechanism, such remote control mechanism being located out of reach of the inmates.

The closure assembly described herein has been shown in connection with a guard or a detention window. The closure assembly, together with the guides therefor, could be used in connection with other types of windows, as for example, office windows, in which event there may or may not be muntin bars extending across the opening forming the ventilating area.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A closure assembly for use with a guard window having muntin bars deterring the egress and ingress of human beings through the window, said muntin bars dividing the window into a plurality of spaces, some of which are glazed, others unglazed for use as a ventilating area, said closure assembly including a frame juxtaposed upon and fixedly attached to the muntin bars bounding the ventilating area, said frame being provided with oppositely disposed channels, a closure slidably mounted in the channels for closing the ventilating area, and an auxiliary frame aligned with and pivotally attached to the fixed frame, said auxiliary frame being removably attached to the guard window, said auxiliary frame having channels aligned with the channels of the fixed frame to permit the closure to slide into the auxiliary frame to thereby open the ventilating area.

2. A closure assembly for use with a guard window having muntin bars deterring the egress and ingress of human beings through the window, said muntin bars dividing the window into a plurality

of spaces, some of which are glazed, others unglazed for use as a ventilating area, said closure assembly including a frame juxtaposed upon and fixedly attached to the muntin bars bounding the ventilating area, said frame being provided with oppositely disposed channels, a closure slidably mounted in the channels for closing the ventilating area, and an auxiliary frame removably attached to the guard window, said auxiliary frame having channels aligned with the channels of the fixed frame to permit the closure to slide into the auxiliary frame to thereby open the ventilating area.

3. A closure assembly for use with a guard window having transversely disposed muntin bars deterring the egress and ingress of human bodies through the window, said muntin bars dividing the window into a plurality of spaces, some of which are glazed, others unglazed for use as a ventilating area, said closure assembly including a pair of frames pivotally attached to each other, one of the frames surrounding the ventilating area, the other frame extending over the window beyond the ventilating area, means for fixedly attaching one of the frames to the muntin bars of the window, means for removably attaching the other frame to the muntin bars, and a closure slidably mounted in said frames, said closure being located in one of the frames when closing the ventilating area and in the other frame when actuated into open position so as to open the ventilating area, and by removing the attachment of the movably mounted frame with the closure therein the closure may be turned inside out for repair.

4. A closure assembly for use with a guard window having transversely disposed muntin bars deterring the egress and ingress of human bodies through the window, said muntin bars dividing the window into a plurality of spaces, some of which are glazed, others unglazed for use as a ventilating area, said closure assembly including a pair of frames, one of the frames surrounding the ventilating area, the other frame extending over the window beyond the ventilating area, a closure, means for guiding the closure to permit the closure to slide from one frame to the other, said closure being moved into one of the frames for closing the ventilating area and into the other frame for opening the ventilating area, means for fixedly attaching one of the frames to the muntin bars of the window, and means for removably attaching the other frame to the muntin bars, said closure being removable with the removably mounted frame when the closure is located therein.

5. A closure assembly for use with a guard window having transversely disposed muntin bars deterring the egress and ingress of human bodies through the window, said muntin bars dividing the window into a plurality of spaces, some of which are glazed, others unglazed for use as a ventilating area, said closure assembly including a pair of interlocking frames, one of the frames surrounding the ventilating area, the other frame extending over the window beyond the ventilating area, means for fixedly attaching one of the frames to the muntin bars of the window, means for removably attaching the other frame to the muntin bars, said frames when attached being aligned with each other, and a closure for opening and closing the ventilating area, said closure being slidably mounted so as to slide from one frame to the other when moving the closure from open to closed position and vice versa, said clo-

sure being removed with the removably mounted frame when the closure is mounted therein to permit servicing of the closure.

6. A closure assembly for use with a guard window having transversely disposed muntin bars deterring the egress and ingress of human bodies through the window, said muntin bars dividing the window into a plurality of spaces, some of which are glazed, others unglazed for use as a ventilating area, said closure assembly including a fixed frame surrounding the ventilating area, said fixed frame being provided with a sill overlapping the muntin bar extending across the bottom of the ventilating area, an auxiliary frame removably attached to the muntin bars and aligned with the fixed frame, said frames being provided with aligned guide means, and a closure slidably mounted in the guide means for closing the ventilating area when positioned in the fixed frame and for opening the ventilating area when positioned in the auxiliary frame.

7. A closure assembly for use with a guard window having transversely disposed muntin bars deterring the egress and ingress of human bodies through the window, said muntin bars dividing the window into a plurality of spaces, some of which are glazed, other unglazed for use as a ventilating area, said closure assembly including a fixed frame surrounding the ventilating area, said fixed frame being provided with a sill overlapping the muntin bar extending across the bottom of the ventilating area, an auxiliary frame pivotally attached to the fixed frame and aligned therewith, said frames being provided with aligned guide means, said auxiliary frame being removably attached to the muntin bars, and a closure slidably mounted upon the guide means for closing the ventilating area when positioned in the fixed frame and for opening the ventilating area when positioned in the auxiliary frame, said closure being adapted to be turned inside out when mounted in the auxiliary frame and the auxiliary frame is detached from the muntin bars.

8. A closure assembly for use with a window provided with a plurality of muntin bars dividing the window into spaces, some of which are glazed and at least one of which is unglazed for use as a ventilating area, said closure assembly including a main frame surrounding the ventilating area, an auxiliary frame pivotally attached to the main frame, said auxiliary frame being removably attached to the muntin bars, a closure mounted for sliding movement from the main frame into the auxiliary frame and vice versa when the auxiliary frame is aligned with the main frame, and an operator pivotally attached to one of the frames and having a sliding contact with the other frame, said operator limiting the rotary movement of the auxiliary frame.

9. A closure assembly for use with a window provided with a plurality of muntin bars dividing the window into spaces, some of which are permanently and fixedly glazed and at least one of which is unglazed for use as a ventilating area, said closure assembly including a main frame surrounding the ventilating area, said frame being fixedly attached to the muntin bars surrounding the ventilating area, an auxiliary frame pivotally attached to the main frame, means for removably attaching the auxiliary frame to the muntin bars surrounding the glazed spaces, and a closure mounted for sliding movement from the main frame into the auxiliary frame and vice versa whenever the auxiliary frame is in line with the main frame, said closure when positioned in

the auxiliary frame when the auxiliary frame is released from the muntin bars being adapted to swing away from the muntin bars for the purpose of servicing.

10. A closure assembly for use with a window provided with a plurality of muntin bars dividing the window into spaces, some of which are glazed and at least one of which is unglazed for use as a ventilating area, said closure assembly including a main frame surrounding the ventilating area, said frame being fixedly attached to the muntin bars surrounding the ventilating area, an auxiliary frame pivotally attached to the main frame, means for removably attaching the auxiliary frame to the muntin bars surrounding the glazed spaces, said means including an operator pivotally attached to the fixed frame and slidably attached to the auxiliary frame, said operator extending parallel to the sides of the frames when the auxiliary frame is aligned with the main frame, and means for locking the operator in parallel relation to thereby hold the auxiliary frame in aligned relation with respect to the fixed frame.

11. A closure assembly for use with a window provided with at least two spaces, one of which is permanently and fixedly glazed and the other unglazed for use as a ventilating area, said window having a window frame enclosing the ventilating area, and a window frame associated with the glazed area, said closure assembly including a main frame surrounding the ventilating area, said main frame being fixedly attached to the window frame surrounding the ventilating area, an auxiliary frame pivotally attached to the main frame, means for removably attaching the auxiliary frame to the window frame associated with the glazed area, and a closure slidably mounted for movement from the main frame of the closure assembly into the auxiliary frame, and vice versa for opening and closing the ventilating area.

12. A closure assembly for use with a window divided into at least two spaces, one of which is permanently and fixedly glazed and the other unglazed for use as a ventilating area, said window having a window frame enclosing the ventilating area, said window frame also surrounding the glazed area, said closure assembly including a main frame surrounding one of said spaces, said main frame being fixedly attached to the window frame, an auxiliary frame pivotally attached to the main frame, means for removably attaching the auxiliary frame to the window frame, and a slidably mounted closure movable from the main frame of the closure assembly into the auxiliary frame and vice versa for opening and closing the ventilating area.

13. A closure assembly for use with a window divided into at least two spaces, one of which is glazed and the other unglazed for use as a ventilating area, said window having a window frame enclosing the ventilating area, said window frame also surrounding the glazed area, said closure assembly including a main frame member surrounding one of said spaces, said main frame member being fixedly attached to the window frame, an auxiliary frame member pivotally attached to the main frame member, means for removably attaching the auxiliary frame member to the main frame member, an operator pivotally attached to one of the frame members and slidably attached to the other frame member, means for locking the operator to hold the auxiliary frame member in aligned relation with

respect to the main frame member, and a closure slidably mounted from the main frame member into the auxiliary frame member and vice versa used in opening and closing the ventilating area.
